DESIGN FOR A SEWING MACHINE FEEDING ATTACHMENT FOR PRODUCING SPIRAL STITCHING

Isidore Klainbard, New York, N. Y.

Application October 29, 1943, Serial No. 111,537

Term of patent 7 years

(Cl. 70—2)

To all whom it may concern:

Be it known that I, Isidore Klainbard, a citizen of the United States, residing at New York, in the county and State of New York, have invented a new, original, and ornamental Design for a Sewing Machine Feeding Attachment for Producing Spinal Stitching, of which the following is a specification, reference being made to the accompanying drawing, forming a part thereof, in which:

Fig. 1 is a top plan view of a sewing machine

feeding attachment for producing spiral stitching, showing my new design.

Fig. 2 is a front elevational view thereof.

Fig. 3 is a top plan view thereof with the split nut released.

I claim:

The ornamental design for a sewing machine feeding attachment for producing spiral stitching, as shown.

ISIDORE KLAINBARD.
